UNITED STATES PATENT OFFICE

WILLIAM H. RIFE, OF CHICAGO, ILLINOIS

DUPLEX ENVELOPE

Application filed September 13, 1928. Serial No. 305,668.

My present invention relates to combination or duplex envelopes, having for its object the provision of a simplified form of envelope of this type together with marginal reinforcing means.

Another object is to provide a duplex envelope of a construction particularly adapted for quantity production.

Other advantages will appear hereinafter.

10 In the drawings, Figure 1 is a plan view of the reverse side of an envelope embodying my invention.

Fig. 2 is a transverse section taken on line 2—2 of Fig. 1, the upper flap being folded 15 over.

Fig. 3 is a face view of the construction shown in Fig. 1.

Fig. 4 is a transverse section taken on line 4—4 of Fig. 3, the upper flap being 20 tucked within one of the compartments.

Fig. 5 is a plan view of the front side of a modified form of my invention.

Fig. 6 is a transverse section taken on line 6—6 of Fig. 5.

25 Fig. 7 is a plan view of the reverse side of the construction shown in Fig. 5, parts being broken away with a view to a clearer disclosure thereof, and

Fig. 8 is a transverse section taken on line 30 8—8 of Fig. 7.

Referring more particularly to the drawings, 11 and 12 designate the top and bottom flaps of a container A, 13 a side closure flap, and 14 a sealing flap,—all joined to a body 35 portion 15, the flaps 11, 12 and 13 providing a compartment 16 which may be sealed against inspection by the flap 14. To the reverse side of the container shown in Fig. 1, I affix by any suitable method, such as gumming or pasting, a blank 17 which is cut to provide top and bottom flaps 18, 19 and end flaps 20, 21. The blank 17 is permanently secured to the container A, as clearly indicated in Figs. 1 and 2, by the gumming 40 of the flaps 19, 20 and 21 directly over the sealing flaps 11, 12 and 13. In this manner a second smaller compartment 22 is formed between the blank 17 and the exterior wall of the flap 11. It will now be observed that 45 if desired, first class mail matter may be

inserted in the smaller compartment 22 and then sealed against inspection by folding over the flap 18 which has the gummed sealing border 18'. If desired, the large compartment 15 may serve for mail matter other than first class by merely tucking in the flap 18 rather than sealing same. When the flap 18 is folded over and gummed to the front side of the container A, the top edge of this container will be thereby strongly reinforced. 55

In the modification shown in Figs. 4 to 8 inclusive, a blank 23 is provided the flap of which instead of being folded over the top edge of the larger container A is placed immediately adjacent the upper edge of the folded flap 12. The blank 23 has top, bottom and side flaps, 24, 25 and 26 respectively, gummed on the reverse sides,—the bottom and side flaps serving to permanently seal the blank to the envelope or container A, thereby providing an additional smaller compartment 27, the contents of which may be closed against inspection by sealing the flap 24 instead of tucking it inside of the smaller 60 compartment. 65

The modified form above referred to is preferably made by taking a conventional mail container of the type used for inclosing catalogues, books, etc., and then affixing thereto the blank 23. This blank may be considered as an envelope from which the front wall alone has been removed, although in actual practice I preferably form the blank 23 from paper stock by machine process, the gumming and affixing to the envelope A then following in sequence. It is to be observed from the configuration of the blank 23 that the same machine employed in the making of conventional envelopes may be used for the cutting and placing of these blanks in proper position. 70 75 80 85

While I have described and illustrated the preferred form of construction for carrying my invention into effect, this is capable of 90 variation and modification without departing from the spirit of the invention. I, therefore, do not wish to be limited to the precise details of construction as set forth, but desire to avail myself of such variations 95 100

and modifications as come within the scope of the appended claim.

What I claim as new and desire to secure by Letters Patent is:

5 A duplex envelope of the character described, comprising a container formed of a blank of paper cut to provide a main body portion having top, bottom, and side flaps folded over to provide a compartment, a second blank cut to provide a second body portion having a bottom flap adapted to be sealed over the line of sealing of said top and bottom flaps of said main body portion, a side flap adapted to be sealed over the line of sealing of one of said side flaps of said main body portion, and a top flap adapted to be folded over the top edge of said main body portion and sealed on the side of said main body portion opposite the side of said main body portion on which said bottom flap of said second body portion is sealed.

In testimony whereof I have signed my name to this specification.

WILLIAM H. RIFE.
